UNITED STATES PATENT OFFICE.

JAMES LESLIE YOUNGHUSBAND, OF CHICAGO, ILLINOIS.

COSMETIC CONTAINER.

Application filed February 21, 1927. Serial No. 169,736.

This invention relates to a cosmetic container, and more particularly to a container the casing sections of which are constructed of a casein product, with said sections provided with metallic clamping rims hingedly connected one to the other to provide a completed container without the use of rivets or the like.

It is an object of this invention to construct a simplified cosmetic container the sections of which are constructed of a casein product such as galalith, with said sections having hingedly connected metallic binding rims clamped on the sections, with one of said binding rims having integral spring tongues adapted to serve as retaining means for holding a compact in place.

It is also an object of this invention to construct a cosmetic container of a casein product without the use of rivets or the like.

It is a further object of this invention to construct a cosmetic container of casing sections having abutting metallic binding rims hinged to one another and clamped to the respective sections with a locking means between said binding rims for holding the container sections in closed position.

It is an important object of this invention to provide a cosmetic container wherein the body and cover are constructed of a casein product such as galalith, with said body and cover having metallic rims clamped thereon and hinged to one another, with one of said rims having spring members struck therefrom for the purpose of retaining a solid powder compact in place within the body portion of the container.

Other and further important objects of this invention will be apparent from the disclosures in the specification and the accompanying drawings.

This invention (in a preferred form) is illustrated in the drawings and hereinafter more fully described.

On the drawings:

Figure 1 is a side elevation of a cosmetic container embodying the principles of this invention.

Figure 2 is a top plan view thereof.

Figure 3 is a top plan view of the bottom section of the container with the cover removed.

Figure 4 is a transverse section of the container taken on line IV—IV of Figure 2.

Figure 5 is a bottom plan view of the cover removed from the container.

Figure 6 is an enlarged fragmentary detail section taken on line VI—VI of Figure 2.

Figure 7 is an enlarged fragmentary detail section taken on line VII—VII of Figure 3 showing a portion of the cover in place.

As shown on the drawings:

The reference numeral 1 indicates a dished or concave bottom or body section constructed of a casein product such as galalith, which is casein treated with formaldehyde and subjected to heavy pressure. Frictionally clamped on the rim or margin of the body section 1 is a U-cross sectioned metallic rim 2, the inner flange 3 of which has a plurality of retaining springs or fingers 4 struck therefrom to serve as flexible retaining means for removably holding a solid powder compact cake seated within the body section. The outer flange 5 is slightly wider or deeper than the inner flange 3 and is slightly curved to conform to the contour of the body section 1, thereby holding the rim frictionally in place on the body section 1. A detent 6 is provided in the outer flange 5 for a purpose hereinafter more fully described. Integrally formed on the rim 2 at a point substantially diagonally opposite the detent 6 is a hinge sleeve 7.

The body section 1 is adapted to be clamped by means of a convex top or cover 8 also constructed of a casein product such as galalith. Frictionally engaged on the rim or margin of the cover 8 is a metallic binding rim 9 having integrally formed thereon a pair of spaced hinge sleeves 10 adapted to be positioned on opposite sides and in alignment with the hinge sleeve 7 to permit a hinge pin 11 to be engaged through the registering hinge sleeves 7 and 10. The binding rim 9 is provided with a plurality of tongues or lugs 12 which project upwardly within the cover and clamp thereagainst to hold the rim 9 secured in position. Integrally formed on the binding rim 9 at a point substantially opposite the hinge sleeves 10 is a locking finger or spring clip 13 having an indent at 14 to lockingly seat in the detent 6 of the bottom rim to hold the cover 8 latched in closed position to the body section 1.

It will thus be seen that a cosmetic container is provided with the body section and cover constructed of a casein product such as galalith, with the abutting rims of the body

and cover bound by metallic rims which are frictionally held in position with said rims hinged together at the rear portion of the container while the front portions of 5 the rims are provided with resilient locking means for holding the cover locked in position on the body section. Resilient means is also provided within the body section, such as the spring lugs 4, which serve to hold a 10 cake of powder or the like in position within the container. The entire device is constructed without the use of rivets, screws, or any other specific retaining means, thereby producing a cosmetic container which 15 can be readily manufactured and assembled at a substantially low cost. I am aware that many changes may be made, and numerous details of construction may be varied through a wide range without departing 20 from the principles of this invention, and I therefore do not purpose limiting the patent granted hereon, otherwise than necessitated by the scope of the appended claims.

I claim as my invention:

25 1. A cosmetic container comprising a body section constructed of a casein product, a metallic binding rim frictionally engaged on said body section, a cover constructed of a casein product, a metallic binding rim for 30 said cover frictionally held in position thereon, hinge means formed on and connecting said binding rims, and latching means integrally formed on said binding rims for holding the cover locked to said body section.

35 2. A cosmetic container comprising a body section and a cover both constructed of galalith, binding rims frictionally engaged on said body section and on said cover, means integrally formed on said binding rims for 40 hingedly connecting said binding rims, and latching means integrally formed on said binding rims for holding said binding rims locked to one another when the cover is in 45 closed position on said body section.

3. A cosmetic container comprising a con-

cave body section constructed of galalith, a convex cover constructed of galalith, a metallic binding rim frictionally engaged on said body section, spring members formed on the inner portion of said binding rim for 50 removably holding a compact seated in the body section, a metallic binding rim frictionally engaged on said cover, hinge means for connecting said binding rims, and resilient latching means carried by the cover binding rim adapted to frictionally engage the body section binding rim to hold the cover locked in place on said body section.

4. A cosmetic container comprising a con- 60 cave body section, a convex top section, metallic binding rims frictionally engaged on the margins of said body section and said cover section, hinge means for connecting said binding rims, and frictionally engag- 65 ing latch means integrally formed on said binding rims for holding the same locked together with the cover section closing said body section.

5. A cosmetic container comprising a con- 70 cave base section, a convex cover section, a binding rim frictionally engaged on said base section, resilient tongues struck from said binding rim to afford a means for holding a compact in place within said body 75 section, a binding rim frictionally engaged on said cover section, means for pivotally connecting said binding rims, and latching means on said binding rims for locking the cover section in place on said base section.

6. A container comprising top and bottom sections of non-metallic material, binding rims on said sections, integral portions on said binding rims hingedly connected together and integral means on said rims for 85 holding contents of the container in position therein.

In testimony whereof I have hereunto subscribed my name at Chicago, Cook County, Illinois.

JAMES LESLIE YOUNGHUSBAND.
